UNITED STATES PATENT OFFICE.

DAVID S. KENNEDY, OF BROOKLYN, NEW YORK, ASSIGNOR TO MERGENTHALER LINO-TYPE COMPANY, A CORPORATION OF NEW YORK.

JUSTIFYING SPACER OR SPACE BAND.

Application filed February 16, 1922. Serial No. 536,883.

To all whom it may concern:

Be it known that I, DAVID S. KENNEDY, a citizen of the United States, residing at Brooklyn, in the county of Kings and State 5 of New York, have invented certain new and useful Improvements in Justifying Spacers or Space Bands, of which the following is a specification, reference being had therein to the accompanying drawing.

10 My invention relates to justifying spacers or spacebands and particularly to that form disclosed in the pending application of James H. Beck, Ser. No. 456,330. As more fully brought out in that application, such spaceband comprises two oppositely tapered or wedge-shaped members, one relatively stationary and the other movable, the latter presenting two marginal bars extending in the direction of its movement and a third centrally located bar extending in the same direction.

25 My present invention, specifically, consists in recessing or reducing the centrally located bar along its inner face, and preferably along its outer face as well, for reasons which will best be understood from the detailed description to follow.

Referring to the drawings:

30 Figs. 1 and 2 represent a composed line of matrices before and after justification, respectively;

Figs. 3 and 4 are views, taken from opposite sides, of my improved spaceband;

Fig. 5 is an enlarged longitudinal section 35 taken on line 5—5 of Fig. 3;

Fig. 5^a is a similar section, but showing the central bar as recessed along its inner face only;

Fig. 6 is an enlarged horizontal section 40 taken on the line 6—6 of Fig. 4;

Fig. 7 is a similar view of the prior form of spaceband;

45 Figs. 8 and 9 are horizontal sections, on an enlarged scale, taken on the lines 8—8 and 9—9 of Fig. 1, respectively;

Figs. 10 and 11 are similar views taken in connection with the prior form of spaceband and illustrating some of its possible defects.

50 As shown in Figs. 1 and 2, the improved spaceband comprises two oppositely tapered or wedge-shaped members A and B, whose outer faces are vertical and whose inner engaging faces are inclined at the same angle 55 so that the outer faces will remain parallel

at all times. The shorter member A is the stationary part, being provided at its upper end with supporting ears A¹ which hold it against movement during justification, while the longer member B is the movable part, being slidably connected to the member A in such manner as to be thrust upwardly through the composed line of matrices Z in performing the justifying action. The movable member B is formed with two longitudinal slots B¹ and presents two marginal bars B² and an intermediate centrally located bar B³, the latter being considerably wider than the other two and beveled on its opposite edges throughout its length or at 60 any rate for a distance equal to the extent of movement of the member B. The relatively stationary member A is formed on its inner or inclined face with a pair of guides A² arranged in the longitudinal slots B¹ 65 and undercut or dovetailed on their inner edges to receive the bevelled edges of the bar B³. The sliding joint or connection thus formed serves to hold the two wedge-shaped members in proper contacting relation, while permitting the member B to be moved relatively to the stationary member 70 A in expanding and contracting the spaceband as a whole. Fig. 1 shows the spacebands in contracted condition, and Fig. 2 75 shows them in expanded condition. It will be noted (Figs. 4 and 6) that the guides A² do not touch the marginal bars B² but are slidably connected solely with the central bar B³. In this connection, it is also pointed 80 out that the length of the guides A² is much greater than the width of the bar B³ (the ratio being more than two to one), thus providing a smooth and easy running engagement between the parts. At their upper 85 ends, the bars B² and B³ merge into a thin connecting web B⁴, the slots B¹ being stopped short of the end of the member B for that purpose; and at their lower ends, the bars are connected together by a longer 90 95 and much thicker web B⁵ which is left at that end of the member B. Between the two webs, the slots B¹ extend clear through the member B so as to allow the latter to be tapered down to the extent indicated and at the same time permit the guides A² to enter the slots in making sliding connection with the bar B³ without projecting beyond the outer or vertical face of the member B. In assembling the two members A and B, 100 105 110

the guides A^2 are slipped over the lower end of the bar B^3 (which, it will be remembered, is bevelled throughout its length), and a headed pin B^6 is then secured to the web B^5 at the extreme lower end of the slots B^1 in position to engage the lower end of the member A and limit the upward movement of the member B . The downward movement of the member B is limited by the direct engagement of the web B^4 with the upper ends of guides A^2 , such being the position of the parts during the circulation of the spaceband through the machine and before justification. In this way, also, the two members of the spaceband are permanently locked together. As thus far described, and except as hereinafter pointed out, the parts are or may be the same as set forth in the aforementioned Beck application, wherein the various advantages are discussed at length.

The characteristic and distinguishing feature of my invention is that the central bar B^3 is recessed or reduced along its opposite side faces, as at b and b' , for a distance at least equal to the extent of movement of the member B , see particularly Figs. 3, 4 and 5. If desired, however, the bar may be recessed only along its inner face, as shown in Fig. 5^a, this being the more important feature, for reasons presently to appear.

In order to bring out the advantages of my improved spaceband, an effort has been made to depict the possible defects which may arise in the use of the prior spaceband. This prior spaceband is shown in cross section in Fig. 7, and it will be noted that the central bar B^3 is of the same thickness as that of the marginal bars B^2 , all three bars having their opposite side faces flush with each other. As a result, it has been found in practise that when such spaceband is composed in line in advance of a recessed matrix Z (this being the usual form for the thicker matrices), the central bar B^3 has a tendency to force the stationary member A into the recess Z' , in the manner illustrated in Fig. 10. This tendency is due to the lateral pressure exerted by the central bar against the stationary member during the justifying action and to the fact that the stationary member is unsupported at the center. Initially, perhaps, the resiliency of the metal might enable the stationary member to spring back into proper shape, but sooner or later the member will lose its resiliency and become permanently distorted. When this occurs, the spaceband cannot lock up properly in the composed line and hence will allow the molten metal to enter between the elements, with the evil results which necessarily follow. Such defect is even more pronounced when the distorted spaceband is composed in advance of an unrecessed matrix, as will be clear from Fig. 11. Other

objections unnecessary to mention also arise.

In the use of my improved spaceband, the foregoing objections are completely obviated. By recessing it along its inner face, the bar B^3 is maintained out of objectionable contact with the opposing face of the stationary member A , and hence is unable to exert any appreciable pressure (if any at all) on said stationary member during the justifying action. On the contrary, the pressure on the stationary member is applied or concentrated wholly by the marginal bars B^2 , which contact therewith only at its opposite edges, where it is firmly and solidly supported by the unrecessed portions of the adjacent matrix, see Figs. 8 and 9. The recessing is further advantageous in that the central bar, being free from pressure, is better able to perform its guiding functions. As before stated, the recessing of the bar B^3 along its outer face is not so important, but it is useful, when the spaceband is composed in line after an unrecessed matrix, in maintaining the bar out of contact with said matrix during the justifying action, see Fig. 9. It can be seen, therefore, that my improved spaceband while possessing all of the advantages of the prior spaceband, is free from the defects which arise in the use of the latter.

In the accompanying drawing, I have shown my invention only in preferred form and by way of example and as applied to the specific form of spaceband noted, but it will be obvious that many changes and alterations may be made therein and in its mode of application without departing from its spirit. For instance, instead of recessing the central bar of the movable section, the stationary member might be recessed along its inner face, or the parts otherwise formed, so as to avoid the objectionable contact referred to. It should be understood, therefore, that I do not limit myself to any specific form or embodiment, except insofar as such limitations are specified in the claims.

Having thus described my invention, what I claim is as follows:

1. A justifying spaceband comprising a movable slotted wedge-shaped member presenting two marginal bars extending in the direction of its movement and an intermediate bar extending in the same direction, and a relatively stationary cooperating wedge-shaped member to which the movable member is slidably connected, the two said members being relatively formed so as to avoid objectionable contact between the opposing faces of the stationary member and the intermediate bar of the movable member during the justifying movements of the latter, for the purpose described.

2. A justifying spaceband comprising a movable slotted wedge-shaped member presenting two marginal bars extending in the

direction of its movement and an intermediate bar extending in the same direction, and a relatively stationary cooperating wedge-shaped member to which the movable member is slidably connected, the said movable member having its intermediate bar recessed or reduced along its inner face to avoid objectionable contact with the opposing face of the stationary member, for the purpose 10 described.

3. A justifying spaceband comprising a movable slotted wedge-shaped member presenting two marginal bars extending in the direction of its movement and an intermediate bar extending in the same direction, and a relatively stationary cooperating wedge-shaped member to which the movable member is slidably connected, the said movable member having its intermediate bar recessed 15 or reduced along its outer face to avoid objectionable contact with the opposing face of an adjacent matrix during the justifying action.

4. A justifying spaceband comprising a movable slotted wedge-shaped member presenting two marginal bars extending in the direction of its movement and an intermediate bar extending in the same direction, and a relatively stationary cooperating 20 wedge-shaped member to which the movable member is slidably connected, the said movable member having its intermediate bar recessed or reduced along both of its side faces, for the purpose described.

35 5. A justifying spaceband comprising a movable slotted wedge-shaped member presenting two marginal bars extending in the direction of its movement and an intermediate bar extending in the same direction, and a relatively stationary cooperating wedge-shaped member having guides arranged in the slots of the movable member and slidably connected solely with the intermediate bar, the two said members being 40 relatively formed so as to avoid objectionable contact between the opposing faces of the stationary member and the intermediate bar of the movable member during the justifying movements of the latter, for the 45 purpose described.

50 6. A justifying spaceband comprising a movable slotted wedge-shaped member presenting two marginal bars extending in the

direction of its movement and an intermediate bar extending in the same direction, and a relatively stationary cooperating wedge-shaped member having guides arranged in the slots of the movable member and slidably connected solely with the intermediate bar, the said intermediate bar being recessed 55 or reduced along its inner face to avoid objectionable contact with the opposing face of the stationary member, for the purpose described.

7. A justifying spaceband comprising a 60 movable slotted wedge-shaped member presenting two marginal bars extending in the direction of its movement and an intermediate bar extending in the same direction, and a relatively stationary cooperating wedge-shaped member having guides arranged in the slots of the movable member and slidably connected solely with the intermediate bar, the said bar being recessed or reduced 65 along its outer face to avoid objectionable contact with the opposing face of an adjacent matrix during the justifying action.

8. A justifying spaceband comprising a movable wedge-shaped member presenting a plurality of bars extending in the direction 70 of its movement, and a relatively stationary cooperating wedge-shaped member slidably connected to a single one of the longitudinal bars of the movable member, the two said members being relatively formed to avoid 75 objectionable contact between the opposing faces of the stationary member and the connected bar of the movable member, for the purpose described.

9. A movable wedge-shaped justifying 80 member presenting two marginal bars extending in the direction of its movement and an intermediate bar extending in the same direction, the said intermediate bar being recessed or reduced along one of its 85 side faces, for the purpose described.

10. A movable wedge-shaped justifying member presenting two marginal bars extending in the direction of its movement and an intermediate bar extending in the same 90 direction, the said intermediate bar being recessed or reduced along both of its side faces, for the purpose described.

In testimony whereof, I have affixed my signature hereto.

DAVID S. KENNEDY.
